UNITED STATES PATENT OFFICE

ALBERT EDWARD HALL, OF SOMERVILLE, AND EDGAR HALL, OF CAMBRIDGEPORT, MASSACHUSETTS, ASSIGNEES, BY DIRECT AND MESNE ASSIGNMENTS, TO ROBERT HOE, OF NEW YORK, N. Y.

STEREOTYPE-CASTING APPARATUS.

No. 801,716.

Specification of Letters Patent.

Patented Oct. 10, 1905.

Application filed October 17, 1900. Renewed March 3, 1904. Serial No. 196,317.

To all whom it may concern:

Be it known that we, ALBERT EDWARD HALL, of Somerville, and EDGAR HALL, of Cambridgeport, in the county of Middlesex and State of Massachusetts, have jointly invented certain new and useful Improvements in Stereotype-Casting Apparatus, of which the following is a specification.

This invention relates to certain improvements in casting-boxes, and more particularly to casting-boxes used for casting stereotype-plates.

Casting-boxes used for casting stereotype-plates as now generally constructed are trunnioned in a frame and arranged to swing to a vertical position in order to receive the molten metal and, after the metal has been poured, into a horizontal position. The cover or cope is then raised and the cast plates removed. Both the casting-box body and the cover or cope are necessarily constructed of heavy metal, and therefore a considerable effort is required not only to swing them on their pivots from the vertical to the horizontal position, but to thereafter raise the cover in order that the cast plate may be removed. In order to facilitate the handling of such boxes, it has been customary to use counterweights of various descriptions, said counterweights operating not only to assist in the movement of the box, but also in the movement of raising the cover. In the usual form such counterweights consist of an iron weight connected to the box and cover by means of a chain, the box and cover operating to raise the counterweight as the box is swung from a vertical to a horizontal position and the counterweight thereafter assisting to raise the cover. These counterweights are not only expensive, but their method of attachment to the box requires the use of a frame, which is also expensive. Furthermore, the operation of a box equipped with counterweights is laborious and the box is slow.

It is one of the objects of this invention to produce a casting-box in which the necessity for extraneous counterweights shall be done away with, the box and cover being arranged so that one of the parts shall act as a counterweight for the other.

A further object of the invention is to produce a casting-box in which only one of the parts of the box need be swung to open and

close it, the other part being arranged so as to be partially stationary with respect thereto, the stationary part acting as a counterweight for the movable part.

A further object of the invention is to produce a casting-box in which the cover and bed act as a counterbalance for each other and in which provision is made for the circulation of cooling liquid.

A further object of the invention is to improve certain details of the mechanism relating to the operation of casting-boxes.

With these and other objects in view the invention consists in certain constructions and in certain parts, improvements, and combinations, as will be hereinafter described, and pointed out in the claims hereunto appended.

In the accompanying drawings, Figure 1 is a side elevation of one form of the improved apparatus, showing the bed and cover of the casting-box locked together in position for pouring. Fig. 2 is a cross-section of the parts on the line 2-2 of Fig. 1. Fig. 3 is a side elevation, the standard and certain parts connected thereto being broken away, the figure illustrating the parts in a slightly-different position from that illustrated in Fig. 1 and in the position preparatory to fully opening the box. Fig. 4 is a side elevation of the box fully opened. Figs. 5 and 6 are front and rear views, respectively, of the box in its fully-opened position, Fig. 6 showing the upper part of the cover broken away. Fig. 7 is a detail of the liquid-transmitting connection between the cover and bed. Fig. 8 is an enlarged sectional detail view illustrating the construction of the matrix-clamp. Fig. 9 is a detail sectional view illustrating a construction of the cover, and Fig. 10 is a view of a cast plate.

Referring to the drawings, which illustrate a preferred embodiment of the invention, the frame shown is composed of a base 11, having standards 18 31 on each side thereof. These standards are or may be connected by cross-bars or tie-rods 12, 13, and 14. The standards 18 are provided with the usual bearings in which in the construction shown the bed or body of the box 15 is mounted to swing, said bed being provided with journals 17. The bed may, as is usual in such boxes, be provided with strengthening-ribs 16, extending lengthwise and crosswise thereof. The

journals 17 instead of, as is usual, being arranged near the middle of the box are arranged between the middle and the lower end of the box, their position being determined 5 by the relative weight of the box and cover. The cover of the box, which is shown as semi-cylindrical, as is usual in boxes for casting printing-plates, is marked 19, and in the preferred form of the construction it will be provided with an internal water-space 20, through 10 which water or other cooling liquid may be caused to circulate, as will be hereinafter described. The cover may be connected to the bed or body in any suitable way; but in the 15 preferred construction and when the cover is hollow the connection will be effected by means of hollow journals 21. In the preferred construction and as is common in this class of boxes the cover will be provided with 20 transverse grooves 24, which form ribs on the concave surface of the cast plate. The upper end of the cover may be and preferably will be beveled or inclined to form in connection with the concave face of the bed a pouring- 25 mouth for the reception of the molten metal.

The matrix-holding devices may be of any suitable description. As shown, there is provided on each side of the bed an angular clamp 25, the construction of this clamp being illustrated in Fig. 8, this clamp in the construction shown also closing the side openings in the bed or body and defining the edge of the cast plate. In the preferred construction this clamp 25 will be connected to the box 30 by suitable hinges, as 27, in order that the clamp may be conveniently turned to release the matrix and plate. The clamp may be provided with a spring to press it firmly against the edges of the matrix. In the construction 35 illustrated in Fig. 8 a coiled spring 28 is provided for this purpose, this spring occupying a socket in one of the members of the hinge, said spring operating against a movable plunger which rests upon it. When the clamp is 40 raised, the plunger is pressed down upon the spring, the spring holding the clamp in both its raised and lower position. When the clamp is fully opened, the swinging member of the hinge may be arranged to bear against 45 a stop 59, formed on the stationary member to prevent the clamp from swinging too far. (See Figs. 5 and 8.)

The space at the bottom between the bed or body 15 and the cover 19 may be closed in 55 any suitable manner. In the construction shown this is effected by the usual head-gage 29, which is suitably shaped to fit the space between the members of the box, this head-gage being in the construction shown pivoted 60 at each end of its semicircular portion to the edge of the bed. The ends of the gage may be, as usual, prolonged and provided with handles, as 30, so that when the box is opened the head-gage may be utilized to push the 65 plate forward. As shown, this head-gage is

slightly recessed at its center, as at 52, Figs. 5 and 6, to form a projection at the end of the plate, which may constitute a guide in the subsequent trimming operation to which such plates are ordinarily subjected.

According to the present invention one of the members of the box is maintained in a substantially vertical position, the other member swinging toward and away from it. In the present instance the cover is the member 75 maintained in the upright position, and the bed or body swings toward and away from the cover. The bed and cover being connected together and the weight of the cover being supported by the bed, it will be understood 80 that by properly positioning the journals of the bed with respect to the weight of the bed and cover the cover will be caused to counterbalance the bed. The bed may therefore be swung up and down toward and away from 85 the cover with great rapidity and with comparatively little exertion, the cover moving vertically, but being maintained always in a substantially vertical position.

The construction by which the part of the 90 box which is maintained in a vertical position is so maintained may be varied widely. In the particular construction shown there is provided a bar 33, which is adjustably connected to a bearing 34, pivoted on the cross-bar 12, before referred to as connecting the standards 31. The other end of this bar is connected to a bearing mounted on a shaft 32, this shaft being supported in bearings mounted on the back of the cover 19, and thus forming 95 an extension from the cover. It will be seen that the rod 33 acts as a link and that through it and the connections before described the cover 19 is pivotally connected to the frame. While the parts might be so constructed that the swinging of the journaled member of the box from the horizontal to the vertical position would serve to bring the two members of the box into completely operative relation with each other and maintain 100 them in this relation during the casting operation in the construction shown, a locking mechanism is employed for holding the parts together during the casting operation. This locking mechanism may be widely varied in 105 construction. As shown, the tie-rod 13 is formed as a shaft and mounted to oscillate in the standards 31. This shaft 13 has fixed upon it a casting 36, to the forward end of which is connected by a pivot 38 a tongue 37, said 110 tongue having a rearward extension 37^a, which serves as a counterweight or balance for it. The pivot 38 connects the casting 36 to the tongue and its tongue about centrally, and said parts are shouldered near the pivot, these 115 shoulders bearing against each other in two different positions. (See dotted lines in Figs. 1 and 4.) The shaft 13 is operated by a handle 35, the forward throw of this handle being 120 controlled by a stop 41. The outer end 125

of the tongue 37 has a notch, as shown, which engages a tailpiece 39 at the foot of the cover as the same is thrown into its vertical position. The casting 36 and the tongue 37 form 5 a toggle, and as the handle 35 is thrown rearwardly this toggle straightens out and forces the lower part of the cover against the bed, the upper part of the cover being thrown forward by the link 33. The locking action of 10 the parts 36 37 takes place after the bed has reached its upright position, so that at this time the link 33 is substantially in its horizontal position.

If desired, a cross-bar 42, bolted to the cover 15 19, having its ends projecting therefrom, may be employed, the projecting ends of this bar bearing, when the box is closed, against the clamps 25, and thus serving to prevent the bed and cover from being forced too closely together.

If desired, a stop 40 may be employed to firmly maintain the bed and cover in position when the box is opened, as illustrated in Fig. 4. This stop 40 in the construction illustrated 25 is mounted on the casting 36 and is thrown into and out of operative position by the movement of the shaft 13.

In opening the box the handle 35 is first thrown from the position illustrated in Fig. 30 1 to the position illustrated in Fig. 4, after which the bed may be swung away from the cover. In the preferred construction, however, a device will preferably be employed to give the box and cover a preliminary separation, 35 this separation taking place before the bed is swung from its vertical to its horizontal position and serving to withdraw the ribs on the cast plate from the grooves 24 in the cover.

40 While any suitable mechanism may be used for this purpose, in the construction shown this preliminary movement is effected by a pair of cams 43, which are fixed on a shaft 44, turning in bearings secured to the rear 45 edges of the cover. This shaft and the shaft 32, before referred to as mounted on the cover, are provided with sprocket-wheels 45. Over these wheels runs a chain 54, and the shaft 32 is provided with a crank-handle 46, by which 50 it is rotated. When the box and cover are constructed as heretofore described, the connections between the two parts are of such a character as to permit the preliminary movement which has just been referred to.

55 In the construction shown the wall of the bed is provided with recesses 55, in which the journals 21 of the cover are received, these recesses being closed by plates 56, bolted to the edge of the bed and being provided with 60 an adjusting-screw 57. This screw is adjustable to permit a movement of the bearings 21 less than the full throw of the cams 43. When the limit allowed by the screw 57 is reached, the bed turns slightly on its journals 65 and throws the upper end of the bed

away from the cover sufficiently to free the ribs of the plate from the grooves in the cover.

When the box is constructed, as shown, to be used with a circulating system of cooling liquid, the construction will be preferably 70 such that a constant current of liquid may be maintained through the water-space 20 in the cover. In the particular construction illustrated the liquid is admitted and discharged through the inlet and outlet pipes 50 and the 75 swinging pipes 47, one of which is shown in detail in Fig. 7. These pipes at each end connect the hollow journals 21 at the bottom of the cover with the journals 17 of the bed, which are also made hollow, so that the bed 80 when swung up and down will maintain its relation to the cover as described without disturbing the flow of water through the pipes which swing with the bed. As illustrated in Fig. 7, one end of each of the connecting 85 water-tubes passes through a stuffing-box 48 and is screwed into the end of one of the pipes 50. The discharge-tubes 49 connect with the water-space 20 in the bed, and the lower ends of these tubes connect with a recess in the 90 bottom of the cover, which leads to one of the hollow journals 21. It will be understood, therefore, that a constant circulation of water is kept up through the bed, the water coming in through one of the pipes 50 and 95 one of the hollow journals 21 and passing out through the pipes 49 and the other hollow journal.

While the construction shown and described embodies the invention in a preferred form, 100 it is to be understood that the invention may be embodied in constructions which differ widely from the one illustrated. It is to be understood also that certain features of the invention may be employed independently of 105 other features, and such independent use is contemplated. The invention is not, therefore, to be limited to the specific construction hereinbefore described and shown.

What is claimed is—

1. In a casting-box, the combination with the body, of a cover, a support upon which one of these parts is mounted to rock, and connections between the body and cover whereby one of said parts is caused to act as a counterweight for the other, substantially as described.

2. In a casting-box, the combination with the body, of a cover, a frame in which one of said parts is mounted to swing, pivotal connections between the frame and the other part, and pivotal connections between the two parts, substantially as described.

3. In a casting-box, the combination with the body and cover, of a frame in which one of said parts is mounted to swing, an extension on the other part, a pivotal connection between the frame and said extension, and pivotal connections between the two parts, substantially as described.

4. In a casting-box, the combination with the body of the box, of a frame in which said body is mounted to swing, a cover pivoted to the box, an extension on the cover, and a pivotal connection between the extension of the cover and the frame, said connection being formed by a link pivoted to the extension and the frame, substantially as described.

5. In a casting-box, the combination with the body of the box and its cover, of a frame, one of said parts being arranged to stand in a substantially vertical plane for all positions of the other part, a frame in which the other part of the box is mounted to swing, pivotal connections between the frame and said vertical part, and pivotal connections between the two parts, substantially as described.

6. In a casting-box, the combination with a vertically-arranged cover, of a frame, a box-body mounted to swing in the frame, pivotal connections between the cover and the box-body, and pivotal connections between the frame and the cover, substantially as described.

7. In a casting-box, the combination with a vertically-arranged cover having an extension, of a swinging body, a frame in which said swinging body is mounted, pivotal connections between the cover and the body, and pivotal connections between the cover and the frame, said pivotal connections being formed by a link which is pivoted to the extension and to the frame, substantially as described.

8. In a casting-box, the combination with the body and cover, of means whereby one of said parts is sustained in a substantially vertical position, means whereby the other part may be swung toward and away from said vertically-arranged part, and connections whereby said vertically-arranged part is caused to act as a counterweight for the other part, substantially as described.

9. In a casting-box, the combination with the body and the cover, of means whereby one of said parts is always sustained at substantially the same angle to a horizontal plane, means for mounting the other part so that it may be swung toward and from the first-named part to open and close the box, and means whereby said first-named part is caused to act as a counterbalance for the other part, substantially as described.

10. In a casting-box, the combination with a frame, of a body pivoted therein, a cover pivoted to the body and arranged to rise and fall as the body is turned on the pivot, and means whereby said cover is always maintained in a substantially vertical position, substantially as described.

11. In a stereotype-casting apparatus, the concave casting box or bed having marginal journals, and adapted to swing thereon from horizontal to about vertical position, in combination with the closed, water-containing, convex cover, connected pivotally at the foot

to the lower end of said box or bed, means for maintaining said cover in an upright position and for moving it laterally and downwardly during the closing movement of the box, and water-circulation pipes connected to the water-space in said cover, substantially as set forth.

12. The concave casting box or bed provided with marginal journals located on a line intermediate between the middle and lower end of said bed, in combination with the convex cover conforming to the concavity of the bed and connected pivotally to its lower end, said parts being so proportioned and united that the cover will approximately counterbalance and aid in raising and lowering the bed, substantially as described.

13. The concave casting box or bed provided with means of adjustment to alternate vertical and horizontal position, in combination with the convex cover pivoted to and approximately counterbalancing said bed, such cover having a curved internal water-space and tubular connections therewith through its hollow journals, whereby a constant water-current is maintained through the interior of said cover and journals, substantially as described.

14. In a stereotype-casting apparatus, the frame comprising transversely-connected sides, the journaled box or bed having a swinging movement in bearings in the frame sides, and the upright cover, pivotally connected to the foot of such box or bed and approximately counterbalancing it in said movement, in combination with supporting mechanism comprising a pivoted lever and jointed toggle-levers and a swinging longitudinal bar mounted on the frame-bars and engaging with the cover, to hold it against the box or bed when both are in upright position, substantially as described.

15. The journaled box or bed, recessed marginally, the cover pivoted at foot thereto upon journals having a limited lateral movement in such recesses, and suitable supporting mechanism serving to hold said parts in working position and to release them, in combination with means adapted to separate the bed and cover laterally before such bed is turned downward, substantially as described.

16. The journaled box or bed formed with marginal recesses near its foot, the convex cover pivoted to the box or bed on journals movable laterally in such recesses, marginal plates closing said recesses, and adjusting-screws therein limiting the lateral movement of said journals, in combination with suitable supporting and releasing mechanism for the bed and cover, and with means adapted to separate them laterally, before the bed is turned down to horizontal position, substantially as described.

17. The concave casting box or bed provided with means of adjustment to alternate verti-

cal and horizontal position, and the vertically-sustained convex cover and means for sustaining it in upright position, such cover having a curved internal water-space extending to the top of the metal receiving-mouth, in combination with hollow journals for said cover, return-tubes spanning the concavity of the cover from top to bottom, and tubular connections admitting water at the bottom of said space and discharging it at the top thereof into such return-tubes continuously during use of the apparatus, the current entering and ultimately leaving the cover through its hollow journals, substantially as described.

18. The tilting box or bed, the convex cover connected at foot thereto, and a supporting and releasing mechanism furnished with a vibrating lever located in rear of said cover, in combination with a rest for the heel of the bed in its horizontal position, such rest being erected on an extension of such lever, and thereby placed in and removed from its oper-

ative position by the movement of said lever, substantially as described.

19. In a casting-box the journaled swinging body or bed, the vertically-sustained cover, and means for sustaining it in upright position, said cover being loosely pivoted to the box and formed with hollow journals and an internal concavo-convex water-space, in combination with water inlet and outlet pipes leading to and from said cover and with interposed swinging pipe-sections, moving with the bed and cover and connecting the hollow journals of the cover with said pipes for continuous water circulation, substantially as described.

In testimony whereof we have affixed our signatures in presence of two witnesses.
